United States Patent Office

Des. 198,349
Patented June 2, 1964

198,349

SPORT EQUIPMENT RACK OR SIMILAR ARTICLE

James B. Saunders, Columbus, Ohio, assignor to Basic Wire Products, Inc., Columbus, Ohio, a corporation of Ohio

Filed Sept. 20, 1963, Ser. No. 76,652

Term of patent 14 years

(Cl. D80—10)

FIG-1

FIGURE 1 is a perspective view of a sport equipment rack or similar article, showing my new design.

I claim:

The ornamental design for a sport equipment rack or similar article, substantially as shown.
